A. M. VAN DOORN

FOUNTAIN DRAWING PEN

Filed Oct. 15, 1924

FIG. 1.

FIG. 2.

FIG. 3.

INVENTOR
A. M. Van Doorn

By *D. F. Woehl*
His Attorney.

UNITED STATES PATENT OFFICE.

ANTHONIUS MARINUS VAN DOORN, OF Utrecht, NETHERLANDS.

FOUNTAIN DRAWING PEN.

Application filed October 15, 1924. Serial No. 743,764.

To all whom it may concern:

Be it known that I, ANTHONIUS MARINUS VAN DOORN, a subject of the Queen of the Netherlands, residing at Utrecht, Netherlands, have invented certain new and useful Improvements in and Relating to Fountain Drawing Pens, of which the following is a specification.

This invention relates to fountain drawing pens of the type having a reservoir adapted to contain ink and a piece of piping for feeding the ink in the fountain to the nib of the pen.

The object of this invention is to provide an improved fountain drawing pen of this type allowing to form without any inconvenience both thin and thick lines until the fountain has been completely emptied.

According to this invention the end of the relatively wide ink feed pipe, which opens between the points of the members of the pen where the ink is required, is partly cut away on opposite sides in accordance with the form of the pointed portions of the members so as to form a fork between the prongs of which a loose wire or stylus, which extends through the entire length of the feed pipe, is adapted to project.

The special construction of the end portion of the feed pipe results in an automatic regulation of the ink feed when the members of the pen are forced together or allowed to separate to form thin or thick lines, respectively. As to the wire or stylus, this partly obstructs the mouth of the relatively wide feed pipe and renders the formation of incrustations of dry ink on the walls of said mouth practically impossible owing to its to and fro motion during the use of the pen, in addition to causing the ink to flow into the nib due its projection from the mouth of the feed pipe.

The nib of the pen is preferably adjustable by means of a screw carried by the comparatively thick wall of the ink feed pipe.

The annexed drawing shows, by way of example only, an embodiment of the invention, Fig. 1 being a side elevational section, Fig. 2 a top view and Fig. 3 a similar view as Fig. 2 but with the top member swung at right angles to the bottom member.

The interior of the lower end of the reservoir or fountain 1 is provided with a screw thread engaged by the similarly screw-threaded portion of the ink feed pipe 2. Said feed pipe, which serves to close the

reservoir 1, carries the pen members 11 and 12 and is provided with a central bore 3 extending through its entire length.

The pipe 2 is reduced in steps towards its end and its end portion is tapered on the sides opposite the pen members so as to form a fork as clearly shown in Fig. 3. The central bore 3 accommodates the stylus 5 weighted by a button 6 on its top end in the reservoir 1. The mouth of the bore 3 is adapted to be closed by a screw-threaded pin 7 provided with a knob 8.

The thickest portion of the wall of the feed pipe is provided on opposite sides with screw-threaded holes receiving screws 9 and 10 acting as pivots for the members 11 and 12, which can be forced together and allowed to separate by thumb nuts 13 and 14 on screws 15, 16 on opposite sides of the central portion of the pipe 2. Said nuts are provided with conical shoulders 17 and 18, respectively, adapted to enter into corresponding holes of the members 11 and 12, respectively, so as to accurately center said members after these have been swung open about their pivots, for instance, for cleaning purposes.

The upper face of the feed pipe 2 is provided with a conical recess 2^a so that the stylus 5 can always easily enter into the bore 3.

It is not necessary for the pin 7 to have a screw engagement with the feed pipe. It could, for instance, simply be tapered. Even when the obturator 7, 8 is altogether dispensed with, the pen would not leak.

What I claim is:

1. In a fountain drawing pen of the class described, an ink reservoir, a feed pipe fitted into the end of said reservoir and having a central bore, a pair of pen members carried by the feed pipe, and said feed pipe having the discharge end thereof partly cut away on opposite sides to correspond to the form of the pointed portions of the pen members, and a stylus member arranged in the hollow bore of the feed pipe and having the point thereof projecting through the cut away portions at the end of the feed pipe and lying between the tips of said pen members.

2. In a fountain drawing pen of the class described, a reservoir, a feed pipe fitting into the reservoir, pen members carried by the feed pipe, said feed pipe having a central feed bore and being obliquely cut away

at opposite sides of its discharge end, thereby to provide a forked discharge opening lying between the points of the pen members, and a stylus wire having a button at its inner end within the reservoir and its outer end being pointed and projecting through the forked end of a feed pipe and lying close to the tip extremities of the pen members.

10 3. In a fountain pen of the class described, a reservoir, and a feed pipe fitted into the reservoir, pen members pivoted to said feed pipe thereby to swing in the plane of their transverse axes and having lateral 15 slots, thumb nuts carried by the medial portions of the feed pipe and adapted to enter said lateral slots of the pen members and having means for clamping and centering said pen members in proper position, and a 20 stylus member for controlling the flow of

ink through said feed pipe normally lying close to the inside portions of the tips of the pen members.

4. In a fountain drawing pen of the class described, a reservoir, a feed pipe fitting 25 into the reservoir, said feed pipe having a central bore and being cut away obliquely at opposite sides of its discharge end to provide a forked portion, pen members having their tip portions lying close to the 30 opposite sides of the forked portion of the feed pipe, means for spreading said pen members apart, a stylus member lying within the bore of the feed pipe, and a plug element adapted to be inserted in the discharge end of the feed pipe when the pen members are laterally separated.

In testimony whereof I affix my signature.

ANTHONIUS MARINUS VAN DOORN.
